UNITED STATES PATENT OFFICE

MAUNSELL B. JACKSON, OF TORONTO, ONTARIO, CANADA

ENGINE STARTER

Application filed March 13, 1928. Serial No. 261,359.

This invention relates to starters for internal combustion engines and more particularly to the type in which a starter pinion is manually moved into meshing engagement with an engine gear and my object is to provide simple and efficient means for accomplishing this without damaging the teeth of either the gear or the pinion.

I attain my object by providing an armature shaft with long pitched threads on which a starter pinion is threaded. On this shaft is disposed a rotatable member on which is disposed a sleeve formed in two parts, one of which is driven directly by manually movable means. A frictional drive connection is provided between the rotatable member and the sleeve parts. The latter have co-operative inclined faces adapted to cause an axial movement of the parts to increase the friction when the manually operable means is moved to start the engine. Means for providing lost motion is provided so that the rotatable member, which carries a spring finger, may be rotated relative to the pinion, which carries a cam. This relative movement of the finger and cam causes the pinion to be axially moved towards the gear and into mesh therewith if the teeth on the pinion are in alignment with the spaces between the teeth on the gear. Should the pinion teeth abut the gear teeth, the spring finger will be compressed until the lost motion has been taken up, whereupon the pinion will be rotated to clear its teeth of the gear teeth so that the compressed spring finger will move the pinion axially again into meshing engagement with the gear. The manually operable means, when it nears the end of its movement, closes a switch to energize the starter motor, whereby the pinion, which is already in mesh with the gear, will be threaded along the shaft to engage the abutment thereon if the pinion is not fully meshed by the manually operable means. The abutment limits the axial movement of the pinion in one direction to form a rotary drive connection between the shaft and pinion threads. When the motor

is energized the shaft runs ahead of the rotatable member until the lost motion means is restored to its initial position, in which position it forms a drive connection between the shaft and member to position the finger to clear the cam when the pinion is de-meshed. The constructions are herein-after more fully described and are illustrated in the accompanying drawings in which

Fig. 1 is a longitudinal section of my starter showing the pinion and spring finger in their normal or inoperative positions;

Fig. 2 a cross section on the line 2—2 in Fig. 1;

Fig. 3 a view similar to Fig. 2, showing the rotatable member moved to take up the lost motion;

Fig. 4 a cross section on a reduced scale on the line 4—4 in Fig. 1;

Fig. 5 a development of the surfaces of the two part sleeve and bushing shown in Fig. 1;

Fig. 6 a longitudinal section of a modified form of starter;

Fig. 7 a horizontal sectional detail of the member and sleeve shown in Fig. 6;

Fig. 8 a longitudinal section of a modified form of starter, in which the sleeve is omitted;

Fig. 9 a longitudinal section of a further modified form of starter in which the pinion has a limited rotary movement relative to the shaft;

Fig. 10 a cross section on the line 10—10 in Fig. 9;

Fig. 11 a side elevation partly in section, of a further modified form of my starter;

Fig. 12 a side elevation, partly in section, of a further modified form of my starter; and

Fig. 13 a side elevation, partly in section, of a still further modified form of my starter.

In the drawings like numerals of reference indicate corresponding parts in the different figures.

Referring to Figs. 1 to 5, 1 is an electric motor having an extended armature shaft 2 provided with long pitched threads 3. A

pinion 4, adapted to be moved axially into and out of mesh with a gear 5 of the engine to be started, is threaded on the threads 3. On the shaft is disposed a rotatable member 6, the ends of which are provided with flanges 7, 8. A cam shaped member, formed as a bent spring finger 9, may be carried on either the flange 7 or the pinion 4. The finger is adapted to engage a cam 10 carried on the other of the pinion or flange parts.

A projection 11 carried by the flange 7 is located between shoulders 12 and 13 formed on a ring 14 keyed at 15 to the shaft 2. The shoulders 12, 13 are spaced apart sufficiently to permit a limited rotary movement of the member 6 relative to the shaft whereby the spring finger 9 is rotated relative to the cam 10. Pressure is thus produced on the pinion tending to axially move it towards the gear. The projection 11 is normally in engagement with the shoulder 12 and when the member 6 is rotated, as hereinafter described, the projection moves towards the shoulder 13 to draw the free end of the spring finger across the cam surface of the cam 10. This movement forces the pinion along the shaft and, if the pinion teeth enter the spaces between the gear teeth, meshes the pinion with the gear. Should the ends of the pinion teeth abut the ends of the gear teeth, the axial movement of the pinion towards the gear will be stopped but the rotary movement of the member relative to the shaft will continue so that the free end of the finger will be pressed back until the projection 11 engages the shoulder 13 and rotates the shaft 2 and thus the pinion teeth sufficiently to clear the gear teeth. The free end of the finger is then free to move the pinion axially again into mesh with the gear.

The member 6 is rotated by means of a sleeve 16 which is formed in two parts 17 and 18. These parts are slightly spaced apart and are disposed on the member 6. The remote ends of the two parts are provided with flanges 19 and 20. Annular disks 21 of friction material, disposed on the member 6, are interposed between flanges 7 and 19; and 8 and 20. The sleeve part 18 is provided with a gear 22 which is meshed with a suitably guided rack 23. The upper end of the rack is bifurcated to receive a switch arm 24 which is manually operated by any well known foot pedal or hand pull-out device to actuate the rack. The adjacent ends of the sleeve parts 17 and 18 are provided with inclined co-operative faces 27 and 28 adapted to move the said parts axially away from one another to form a frictional drive connection, by means of the disks 21, flanges 7 and 19—8 and 20, between the sleeve 16 and member 6. A spring 26 tends to rotate the part 17 relative to the

part 18 to set the frictional drive connection between the sleeve and member to normally provide a friction "drag" or brake for a purpose which will hereinafter appear. The rack 23 and gear 22 are adapted, when the manually operable device is actuated to start the engine, to rotate the sleeve part 18 in the direction of rotation indicated by the arrow and opposite to that imparted to part 17 by the spring 26 whereby the sleeve parts 17, 18 are given a further axial movement to increase the friction between the flanges of the sleeve and member.

To facilitate the relative movements of the inclined faces 27, 28, a ball 29 is carried between the faces of each set. The balls are retained by a transversely split bushing 30 carried between the member 6 and the sleeve 16 and by a ring 31.

The rack 23 and the other manually operable means for actuating the rack are returned, by means of a spring 32, to their inoperative positions. The lower end of the rack is tubular to receive one end of the spring, the other end of which engages a plug 33. A pin and enlarged hole connection 34 limits the upward movement of the switch arm 24 relative to the rack.

The mode of operation is as follows. When the rack 23 is depressed by the operator to start the engine, the sleeve part 18 is driven in a direction of rotation indicated by the arrow to rotate the member 6. This rotary movement of the part 18 takes up all possible movement of the inclined faces 28 relative to the faces 27 whereby the friction is increased to its maximum to ensure the driving of the member 6. This member is thus rotated relative to the shaft to cause the cam shaped spring finger 9 to move the pinion 4 axially of the shaft as hereinbefore described. If the pinion teeth abut the gear teeth the rotary movement of the member 6 is continued whereby the projection 11 engages the shoulder 13 to rotate the shaft 2 and thus the pinion until the spring finger 9 is permitted to move the pinion axially into meshing engagement with the gear.

As the switch arm 24 nears the end of its movement for depressing the rack 23, a lug 35 on the switch arm engages the plunger 36 of a spring actuated plunger switch for controlling the electric energy to the motor 1. The switch is normally open and when closed by the switch arm 24 the motor will be energized to rotate the shaft 2.

If the pinion be not fully meshed with the gear, the former will be threaded along the shaft into engagement with an abutment 37 which limits the axial movement of the pinion whereby the latter is rotated with the shaft.

When the shaft is rotated by the motor, the shoulder 12 moves relative to the pro-

jection 11 until it engages the latter so that the rotatable member 6 is driven with the shaft. The spring finger 9 is thus positioned in its initial position relative to the shaft threads so that cam 10 will clear the finger when the pinion is automatically demeshed by the engine gear.

Immediately the rotatable member 6 is driven by the shaft 2 the frictional drive connection between the member 6 and the sleeve part 17 causes the latter to be slightly rotated relative to the sleeve part 18, which is held stationary by means of the rack and switch arm when the operator is energizing the motor. The inclined faces 27 are thus moved relative to the faces 28 to relieve the increased friction, between the rotatable member and the sleeve parts, which was applied by the manually operable means when actuated to start the engine as hereinbefore described. The normal or constant friction exerted by the spring 26 on the frictional drive connection between the flanges 7, 19 and 8, 20 of the rotatable member and sleeve parts is adapted to permit the connection to slip to permit the shaft to rotate the member 6 relative to the sleeve parts 17, 18. This friction serves as a brake or drag on the rotatable member to prevent it from overrunning the shaft to re-mesh the pinion, when the motor is de-energized.

When the operator permits the spring 32 to return the rack 23 and switch arm 24 to their initial position, the motor circuit 51 will be opened to de-energize the motor. This return movement of the rack rotates the part 18 in a direction opposite to that indicated by the arrow, in Fig. 1, and therefore returns the parts 17 and 18 to their initial position.

In Figs. 6 and 7 a modified arrangement of the starter is shown. The rotatable member 6^a disposed on the shaft 2^a is provided with flanges 7^a and 8^a. The flange 8^a is provided with a projection 11^a freely carried between shoulders 12^a and 13^a, formed by a recess in the periphery of a ring 14^a secured to the shaft. A one-piece sleeve 16^a, disposed on the member 6^a, is provided with a flange 19^a. A ring 21^a of friction material is interposed between the flanges 19^a and 7^a. A spring 26^a disposed on the member 6^a and having its ends engaging antifriction washers 38 bearing against the flange 8^a and against the end of the sleeve 16^a, sets the frictional drive connection between the sleeve and member. The sleeve 16^a is rotated, by means of a manually operable lever 23^a having a pin and helical slot connection 22^a with the sleeve, to rotate the member 6^a. Engaging means comprising a spring finger 9^a and a cam 10^a is provided between the member 6^a and pinion 4^a whereby one movement of the lever will move the pinion axially and rotarily, if necessary, to mesh it with the en-

gine gear 5^a. The pin and slot connection 22^a is so arranged that the friction between the flanges 19^a and 7^a is increased during the movement of the lever 23^a to start the engine. The lever is provided with a lug 35^a for operating the plunger 36^a to close the motor circuit when the lever nears the end of its movement. A spring 32^a tends to return the lever and the other manually operable parts to their inoperative positions, the spring 32^a being considerably weaker than the spring 26^a.

In Fig. 8 the sleeve 16 or 16^a is not used. The frictional drive connection between the manually operated device 25 and rotatable member 6^b is formed by a spring-tensioned cable 23^b. The cable has one or more windings on the member and is connected with the switch arm 24^b and the spring 26^b to compress the latter when the device 25 is operated to start the engine. The low portion of the cam shaped finger member 9^b normally engages an axially directed projection 39 carried by the pinion 4^b. During the movement of the projection 11^b towards the shoulder 13^b the cam or helical shaped portion of the finger 9^b engages the projection 39 to move the pinion axially into mesh with the gear 5^b or against the end thereof. In latter case the continued rotary movement of the member 6^b rotates, by means of the projection 11^b and shoulder 13^b, the shaft 2^b and thus the pinion 4^b, to clear its teeth from those of the gear which permits the finger 9^b to continue the axial movement of the pinion into mesh with the gear. The lug 35^b then closes the plunger switch 36^b to energize the motor 1^b. The shaft 2^b and thus the shoulder 12^b rotates relative to the member 6^b until the said shoulder engages the projection 11^b to rotate the member and position the finger to clear the projection 39 when the pinion is de-meshed from the gear.

In Figs. 9 and 10 a slightly modified arrangement of the lost motion device for permitting a limited relative movement between the finger 9 and cam 10 is shown. The pinion 4^c is loosely threaded on the shaft threads 3^c so that the shaft 2^c may be rotated relative to the pinion which is weighted, by a collar 40, to increase its inertia. The cam shaped finger 9^c is carried by the rotatable member 6^c which is formed integral with or secured to the shaft and is rotated by the manually operable cable 23^c. When the latter is operated to start the engine the finger 9^c and shaft 2^c are rotated relative to the cam 10^c and pinion 4^c respectively, to move the pinion axially of the shaft. Should the pinion teeth abut the gear teeth the continued rotary movement of the rotatable member and shaft will bring the sides *a* of the shaft threads into engagement with the pinion threads to rotate the pinion to clear its teeth whereupon the cam shaped spring 130

finger will again move the pinion axially into meshing engagement with the gear.

In Fig. 11 a spring actuated pin 9^d is substituted for the cam shaped spring finger shown in the other views. Any suitable means may be employed, such as the cable 23^d, to rotate the member 6^d manually. In the constructions hereinbefore described the rotatable member is adapted to rotate the shaft and thus the pinion to clear the pinion teeth when they abut the gear teeth. In this modification a pin 41 carried by the member is adapted to engage a projection 42 carried by the pinion 4^d whereby the latter is rotated, if necessary, directly by the rotatable member. The shoulder 12^d for engaging the projection 11^d is formed by a pin carried by the shaft 2^d.

In Fig. 12, I show a spring actuated pin 9^e engaging a pocket 10^e carried by the pinion 4^e. The pin is carried on a stem 43 journaled in the rotatable member 6^e so that as the latter is rotated the stem may rotate slightly to permit the outer end of the pin to remain in its pocket while it is axially or rotarily moving the pinion. The rotating movement of the stem on its axis is limited in both directions by stops 44 and 45 which are adapted to engage an arm 46 carried by the stem. A spring 47 tends to return the arm 46 to its initial position in engagement with the stop 44. A nut 48 limits the outward movement of the pin, and the shoulder 12^e positions the rotatable member so that the pin will engage the pocket when the pinion is de-meshed.

Fig. 13 shows a hook 49 on the spring finger 9^f for engagement with a lug 50 on the cam 10^f, whereby the pinion 4^f may be rotated, if necessary, by the rotatable member 6^f without rotating the shaft 2^f.

The cable drive connections shown in Figs. 8 to 13 are adapted to frictionally engage the rotatable members to rotate the latter, and these drive connections are adapted to slip when the rotatable members are being driven by the armature shafts to position the cam shaped members on the rotatable members to clear the cams or projections on the pinions when the latter are de-meshed. It will be distinctly understood that the drive connections shown in Figs. 1 or 6 may be substituted for the drive connections shown in Figs. 9 to 13.

55 What I claim is:

1. An engine starter comprising a rotatable shaft; a starter pinion having a drive connection with the shaft and adapted to be moved axially to mesh with a gear of an engine to be started; a rotatable member on the shaft; manually operable means for rotating said member; and means whereby the said member is adapted, when rotated not more than a predetermined distance, to move the pinion axially and if the pinion

teeth meet end to end with the gear teeth to resiliently hold them in engagement therewith and thereafter positively rotate said pinion to clear the teeth of the gear to permit a further axial movement.

2. An engine starter comprising a rotatable shaft; a starter pinion having a drive connection with the shaft and adapted to be moved axially to mesh with a gear of an engine to be started; a rotatable member on the shaft; manually operable means for rotating said member; and means whereby the said member is adapted when rotated not more than a predetermined distance to impart an axial movement to the pinion and thereafter by continued rotary movement to rotate the pinion if the teeth thereof meet end to end with the teeth of the gear, whereby the teeth are cleared to permit a further axial movement of the pinion.

3. An engine starter comprising a rotatable shaft; a starter pinion having a drive connection with the shaft and adapted to be moved axially to mesh with a gear of an engine to be started; a rotatable member on the shaft; manually operable means for rotating said member; and means whereby the said member is adapted when rotated not more than a predetermined distance to impart an axial movement to the pinion and thereafter by continued rotary movement to rotate the pinion if the teeth thereof meet end to end with the teeth of the gear, whereby the teeth are cleared to permit a further axial movement of the pinion, the last mentioned means including a spring cushioning device adapted to be tensioned by the movement of the rotatable member, if the axial movement of the pinion is temporarily stopped, to effect the initial meshing movement of the pinion when its teeth are brought to meshing position.

4. An engine starter comprising a rotatable shaft; a starter pinion having a drive connection with the shaft and adapted to be moved axially to mesh with a gear of an engine to be started; a rotatable member; manually operable means for rotating said member; and means whereby the said member is adapted when rotated not more than a predetermined distance to impart an axial movement to the pinion and thereafter by continued rotary movement to rotate the pinion if the teeth thereof meet end to end with the teeth of the gear, whereby the teeth are cleared to permit a further axial movement of the pinion, the last mentioned means including a drive connection between the manually operable means and the said rotatable member adapted to permit slippage.

5. An engine starter comprising a rotatable shaft; a starter pinion having a drive connection with the shaft and adapted to be moved axially to mesh with a gear of an engine to be started; a rotatable member;

- manually operable means for rotating said member; means whereby the said member is adapted when rotated not more than a predetermined distance to impart an axial movement to the pinion and thereafter by continued rotary movement to rotate the pinion if the teeth thereof meet end to end with the teeth of the gear, whereby the teeth are cleared to permit a further axial movement of the pinion; a frictional drive connection between the manually operable means and the said rotatable member; and means normally setting the frictional drive connection and adapted to increase the friction when the manually operable means is actuated to start the engine. 5 70 75 80
6. An engine starter comprising a rotatable shaft; a starter pinion threaded on the shaft and adapted to be moved axially thereof to mesh with a gear of an engine to be started; a rotatable member on the shaft; manually operable means for rotating the said member; means whereby the said member is adapted when rotated not more than 20 a predetermined distance to impart an axial movement to the pinion and thereafter by continued rotary movement to rotate the pinion if the teeth thereof meet end to end with the teeth of the gear whereby the teeth are cleared to permit a further axial movement of the pinion; a projection carried by the shaft adapted to engage and rotate the member to position the latter in its initial position relative to the pinion to permit the thread to de-mesh the pinion, the manually operable means including a sleeve formed in two parts disposed on the member, the said parts having co-operative inclined faces; a frictional drive connection between the sleeve and the member; and spring means 85 tending to set the frictional drive connection, the inclined faces being adapted to increase the friction when the sleeve is actuated to start the engine. 90
7. An engine starter comprising a rotatable shaft; a starter pinion threaded on the shaft and adapted to be moved axially to mesh with a gear of an engine to be started; a rotatable member on the shaft; manually operable means for rotating the said member; means whereby the said member is adapted when rotated not more than a predetermined distance to impart an axial movement to the pinion and thereafter by continued rotary movement to rotate the pinion if the teeth thereof meet end to end with the teeth of the gear whereby the teeth are cleared to permit a further axial movement of the pinion. 95 100 105
8. An engine starter comprising a rotatable shaft; a starter pinion threaded on the shaft and adapted to be moved axially to mesh with a gear of an engine to be started; a rotatable member on the shaft; manually operable means for rotating the said member; means whereby the said member is adapted to when rotated not more than a predetermined distance to impart an axial 110 115 120 125 130

movement to the pinion and thereafter by continued rotary movement to rotate the pinion if the teeth thereof meet end to end with the teeth of the gear, whereby the teeth 5 are cleared to permit a further axial movement of the pinion; a frictional drive connection between the manually operable means and the said rotatable member; and means adapted to increase the friction when the manually operable means is actuated to 10 start the engine.

12. An engine starter comprising a rotatable shaft; a starter pinion having a drive connection with the shaft and adapted to be moved axially to mesh with a gear of an engine to be started; a rotatable member; manually operable means for rotating said member; means for imparting an axial movement to the pinion by the rotation of 15 the member; means adapted to rotate the pinion by the rotation of the member; and means for providing lost motion whereby the member may rotate relative to the pinion to effect an axial movement of the pinion before the latter is rotated by the member 20 to clear its teeth of the gear teeth to permit a further axial movement.

13. An engine starter including a rotatable shaft; a starter pinion having a drive connection with the shaft and adapted to be moved axially to mesh with a gear of an engine to be started, the said drive connection serving to rotate the pinion if the teeth on the latter meet end to end with 30 the teeth on the gear; a member on the shaft adapted to rotate the latter; means for imparting an axial movement to the pinion by the rotation of the member; manually operable means adapted to rotate the member; and means for providing lost motion 35 whereby the member may rotate relative to the pinion to effect an axial movement of the pinion before the shaft is rotated by the member to rotate the pinion to clear its teeth of the gear teeth to permit a further axial movement.

14. An engine starter including a rotatable shaft; a starter pinion having a drive connection with the shaft and adapted to be moved axially to mesh with a gear of an engine to be started, the said drive connection serving to rotate the pinion if the teeth on the latter meet end to end with the teeth 50 on the gear; and member on the shaft adapted to rotate the latter; engaging means, including a spring, for causing an axial movement of the pinion by the rotation of the member; manually operable means adapted to rotate the member; and means for providing lost motion whereby the member may rotate relative to the pinion to effect an axial movement of the pinion before the shaft is rotated by the member to 55 rotate the pinion to clear its teeth of the

gear teeth and to thus permit a further axial movement.

15. An engine starter including a rotatable shaft; a starter pinion threaded thereon and axially movable thereof to mesh with a gear of an engine to be started, the said thread serving to rotate the pinion if the teeth on the latter meet end to end with the teeth on the gear; a member having a limited rotary movement relative to the shaft; engaging means, including a spring, between the member and pinion for causing an axial movement of the pinion; and manually operable means adapted to rotate the member relative to the pinion to effect an axial movement of the pinion and, if necessary, to take up said limited rotary movement whereby the shaft will rotate the pinion teeth to clear the gear teeth to permit a further axial movement.

16. In a starter for use with an internal combustion engine having a gear adapted to rotate the crankshaft thereof, the combination of starter mechanism including a shaft; a starter pinion having a drive connection with the shaft and adapted to be moved axially to mesh with the gear, the said drive connection serving to rotate the pinion if the teeth on the latter meet end to end with the teeth on the gear; a cam shaped member carried by one of the said shaft and pinion parts and adapted to engage the other of the said shaft and pinion parts, the said member and its said engaging part having a limited rotary movement relative to one another whereby an axial movement of the pinion is effected; and manually operable means adapted to rotate one of the said member and its said engaging part relative to the other to effect an axial movement of the pinion and, if necessary, to take up the said limited rotary movement whereby the shaft will rotate the pinion teeth to clear the gear teeth to permit a further axial movement.

17. An engine starter including a rotatable shaft; a starter pinion having a drive connection with the shaft and adapted to be moved axially to mesh with a gear of an engine to be started, the said drive connection serving to rotate the pinion if the teeth on the latter meet end to end with the teeth on the gear; a member on the shaft adapted to rotate the latter; engaging means between the pinion and member for causing an axial movement of the pinion by the rotation of the member; means adapted to frictionally engage the member to rotate it; manually operable means adapted to cause the friction means to rotate the member; and means for providing lost motion whereby the member may rotate relative to the pinion to effect an axial movement of the pinion before the shaft is rotated by the member to rotate the pinion to clear its

teeth of the gear teeth and to thus permit a further axial movement.

18. In a starter for use with an internal combustion engine having a gear adapted to 5 rotate the crankshaft thereof the combination of starter mechanism including a motor; a circuit connected with the motor and including means for closing the circuit; a shaft driven by the motor; a starter pinion 10 having a drive connection with the shaft and adapted to be moved axially to mesh with the gear, the said drive connection serving to rotate the pinion if the teeth on the latter meet end to end with the teeth on 15 the gear; a cam shaped member carried by one of the said shaft and pinion parts and adapted to engage the other of the said shaft and pinion parts, the said member and its said engaging part having a limited rotary movement relative to one another whereby an axial movement of the pinion is effected; and manually operable means 20 adapted to actuate the circuit closing means to close the circuit and adapted to rotate 25 one of the said member and its said engaging part relative to the other to effect an axial movement of the pinion and, if necessary, to take up the said limited rotary movement whereby the shaft will rotate the 30 pinion teeth to clear the gear teeth to permit a further axial movement before the circuit is closed.

19. An engine starter including a rotatable shaft; a starter pinion having a drive 35 connection with the shaft and adapted to be moved axially to mesh with a gear of an engine to be started, the said drive connection serving to rotate the pinion if the teeth on the latter meet end to end with the teeth on 40 the gear; a cam shaped member carried by one of the said shaft and pinion parts and adapted to engage the other of the said shaft and pinion parts, the said member and its said engaging part having a limited rotary 45 movement relative to one another whereby an axial movement of the pinion is effected; manually operable means adapted to rotate one of the said member and its said engaging part relative to the other to cause the pinion to be axially moved and, if necessary, to take up the said limited rotary 50 movement whereby the shaft will rotate the pinion teeth to clear the gear teeth to permit a further axial movement; and a frictional drive connection between the manually operable means and one of the said member and its said engaging part.

20. An engine starter including a rotatable shaft; a starter pinion having a drive 55 connection with the shaft and adapted to be moved axially to mesh with a gear of an engine to be started, the said drive connection serving to rotate the pinion if the teeth on the latter meet end to end with the teeth on the gear; a member on the shaft adapted

to rotate the latter; engaging means, including a spring, for causing an axial movement of the pinion by the rotation of the member; manually operable means having a frictional driving connection with the member; means adapted to increase the friction when the manually operable means is actuated to start the engine; and means for providing lost motion whereby the member may rotate relative to the pinion to effect an axial movement of the pinion before the shaft is rotated by the member to rotate the pinion to clear its teeth of the gear teeth and to thus permit a further axial movement.

21. An engine starter including a rotatable shaft; a starter pinion threaded thereon and axially movable thereof to mesh with a gear of an engine to be started, the said thread serving to rotate the pinion if the teeth on the latter meet end to end with the teeth on the gear; a member having a limited rotary movement relative to the shaft; engaging means, including a spring, between the member and pinion for causing an axial movement of the pinion; a sleeve disposed on the member; a frictional drive connection between the member and the sleeve; and manually operable means having a drive connection with the sleeve to cause the rotation of the member relative to the pinion to effect an axial movement of the pinion.

22. An engine starter including a rotatable shaft; a starter pinion having a drive connection therewith and axially movable thereof to mesh with a gear of an engine to be started, the said drive connection serving to rotate the pinion if the teeth on the latter meet end to end with the teeth on the gear; a member having a limited rotary movement relative to the shaft; spring and cam engaging means between the member and pinion for causing an axial movement of the pinion; a sleeve disposed on the member; manually operable means for rotating the sleeve; a frictional drive connection between the sleeve and the member; means normally setting the frictional drive connection and adapted to increase the friction when the manually operable means is actuated to start the engine.

23. An engine starter including a rotatable shaft; a starter pinion having a drive connection therewith and axially movable thereof to mesh with a gear of an engine to be started, the said drive connection serving to rotate the pinion if the teeth on the latter meet end to end with the teeth on the gear; a member having a limited rotary movement relative to the shaft; engaging means, including a spring, between the member and pinion for causing an axial movement of the pinion; a sleeve formed in two parts disposed on the member; a gear carried by one of the said sleeve parts; manually oper-

able means including a rack meshed with the gear on the sleeve part; a frictional drive connection between one of the said parts and the member; and means tending to set the frictional drive connection, the said sleeve parts having inclined co-operative faces for axially moving the parts away from one another to increase the friction when the rack is moved in one direction to start the engine.

24. An engine starter including a rotatable shaft; a starter pinion having a drive connection therewith and axially movable thereof to mesh with a gear of an engine to be started, the said drive connection serving to rotate the pinion if the teeth on the latter meet end to end with the teeth on the gear; a member having a limited rotary movement relative to the shaft; spring and cam engaging means between the member and pinion for causing an axial movement of the pinion; a sleeve formed in two parts disposed on the member; a gear carried by one of the said sleeve parts; manually operable means including a rack meshed with the gear on the sleeve part; a frictional drive connection between the said parts and the member, the said sleeve parts having inclined co-operative faces for axially moving the parts away from one another to set the frictional drive connection when the rack is moved in one direction to start the engine; and antifriction means engaging the said co-operative faces.

25. In a starter for use with an internal combustion engine having a gear adapted to rotate the crankshaft thereof the combination of starter mechanism including a motor; a circuit connected with the motor and including means for closing the circuit; a shaft driven by the motor; a starter pinion having a drive connection with the shaft and adapted to be moved axially to mesh with the gear; a rotatable member; manually operable means adapted to actuate the circuit closing means to close the circuit and adapted to rotate said member; and means whereby the said member is adapted when rotated not more than a predetermined distance to impart an axial movement to the pinion and thereafter by continued rotary movement to rotate the pinion if the teeth thereof meet end to end with the teeth of the gear, whereby the teeth are cleared to permit a further axial movement of the pinion before the circuit is closed.

26. An engine starter comprising a rotatable shaft; a starter pinion threaded on the shaft and adapted to be moved axially thereof to mesh with a gear of an engine to be started; a rotatable member on the shaft; manually operable means for rotating the said member; means whereby the said member is adapted when rotated not more than a predetermined distance to impart an axial

movement to the pinion and thereafter by continued rotary movement to rotate the pinion if the teeth thereof meet end to end with the teeth of the gear whereby the teeth are cleared to permit a further axial movement of the pinion; and a projection carried by the shaft adapted to engage and rotate the member to position the latter in its initial position relative to the pinion to permit the thread to demesh the pinion.

27. In a starter for use with an internal combustion engine having a gear adapted to rotate the crankshaft thereof, the combination of starter mechanism including a rotatable shaft; a starter pinion having a drive connection with the shaft and adapted to be moved axially to mesh with the gear; a cam shaped member carried by one of said shaft and pinion parts and adapted to engage the other of said shaft and pinion parts, the said member and its said engaging part having a limited rotary movement relative to one another whereby an axial movement of the pinion is effected; manually operable means adapted to rotate one of said members and its said engaging part relative to the other to effect an axial movement of the pinion and, if the teeth on the pinion meet end to end with the teeth on the gear, to take up said limited rotary movement and to rotate the pinion until its teeth clear the gear teeth to permit further axial movement of the pinion.

Signed at Toronto, Canada, this 7th day of March, 1928.
